(57) **CLAIM**

I claim the ornamental design for beverage dispensing devices, as shown and described.

DESCRIPTION

FIG. 1 is front elevation view of an embodiment of the claimed design;

FIG. 2 is a rear elevation view thereof;

FIG. 3 is a right elevation view thereof;

FIG. 4 is a top, front perspective view thereof;

FIG. 5 is a top, front right perspective view thereof;

FIG. 6 is a top, rear perspective view thereof; and,

FIG. 7 is a top, rear left perspective view thereof.

The ornamental design which is claimed is shown in solid lines in the drawings. The broken lines in the drawings are for illustrative purposes only and form no part of the claimed design.
